UNITED STATES PATENT OFFICE.

WILLIAM A. LOWERY, OF SUMMIT, GEORGIA, ASSIGNOR TO THE LOWERY LOCK COMPANY.

AUTOMOBILE-LOCK.

1,384,075.

Specification of Letters Patent. Patented July 12, 1921.

Application filed April 23, 1920. Serial No. 376,048.

To all whom it may concern:

Be it known that I, WILLIAM A. LOWERY, a citizen of the United States, residing at Summit, in the county of Emanuel and State 5 of Georgia, have invented a new and useful Automobile-Lock, of which the following is a specification.

This invention relates to automobile locks, and more particularly to locks to be employed in connection with transmission or 10 fly wheel casings, the present showing being especially designed for attachment to Ford transmission casings.

The primary object of the invention is 15 to provide a device of this character operating in conjunction with the fly wheel of an engine, to lock the fly wheel against movement, thereby preventing unauthorized persons from starting the car.

20 A further object of the invention is the provision of novel means operating simultaneously with the fly wheel lock, for locking the device to the transmission casing; thus eliminating the possibility of the cover 25 of the device being removed, to accomplish the operation of the lock.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 35 within the scope of what is claimed, without departing from the spirit of the invention.

Referring to the drawings:—

Figure 1 illustrates a fragmental side elevational view of a transmission casing, the 40 same being partly broken away to illustrate the relation of the locking device to the fly wheel of the motor.

Fig. 2 illustrates a bottom plan view of the lock.

45 Fig. 3 illustrates a sectional view taken through the locking device.

Fig. 4 illustrates a bottom plan view of the device, showing the locking arm in a locking position.

50 Referring to the drawings in detail, the reference character 5 designates generally, a transmission or flywheel casing which is provided with the usual opening 6 to permit of access to the interior thereof, the casing 55 being shown as housing the usual transmis-

sion of the motor vehicle, together with the fly wheel of the motor which operates in close proximity to the transmission.

The device forming the subject matter of the present invention, includes a supporting 60 plate 8 which is of a formation to correspond with the outline of the opening 6, the supporting plate being however, slightly larger than the opening to permit the same to be secured to the transmission casing at 65 points adjacent to the opening, so that the plate will supplement the usual transmission cover plate.

One end of the supporting plate 8 is turned up as at 9 to provide a locking flange 70 to receive the inturned end 10 of the false cover 11, the rear end of which is turned down as at 12, to embrace the lower end of the supporting plate to guard the same to prevent an instrument from being inserted 75 under the lower end of the supporting plate, to pry or otherwise displace the supporting plate.

The supporting plate 8 is also provided with an elongated opening indicated at 13 80 adapted to accommodate the depending hook 14 which is slotted as at 15, the slotted portion being provided to receive a portion of the pivoted latch member 16 automatically operated, in a manner to be hereinafter 85 more fully described, so that the false cover 11 will be locked to the supporting plate 8.

Formed substantially centrally of the supporting plate is an opening 17 adapted to accommodate the tubular member 18 which 90 accommodates the tumbler barrel 19, formed preferably of case hardened steel, so that the purpose of the invention could not be defeated by sawing the tubular member 18, to disconnect the locked tumblers. An operating rod 20 extends through an opening 95 formed at the base of the tubular member 18, the tubular member is however formed integral with the body portion 21 of the locking device, which is secured to the under 100 surface of the supporting plate 8 as by means of the rivets 22.

The upper end of the operating rod 20 has connection with the tumbler support 23, of the usual lock construction, the tumblers 105 thereof indicated at 24 being disposed to extend into the cut out portions 25 of the tumbler barrel 19 to lock the tumbler support against rotary movement. The lower end of the operating rod 20 terminates at a 110

point below the lower edge of the body portion 21 and has connection with the arm 26, in a manner to cause the arm 26 to rotate upon rotary movement of the operating rod 20.

One end of the arm 26 extends at right angles to the body portion thereof, and is disposed in the slotted portion 27 of the controlling arm 28, which is curved and provided with a slotted portion 29 adjacent to the outer end thereof, the slotted portion 29 being provided to accommodate the pin 30, formed on the locking arm 31, so that the locking arm may automatically adjust itself to fly wheels operating at various distances from the locking arm 30. This locking arm 31 is pivoted to the body portion 21, as by means of the pivot pin 32 positioned in a suitable opening formed in the body portion 21 and secured in the opening by means of the set screw 33, there being a head 34 provided on the lower end of the pin 32 to prevent displacement of the locking arm 31. The inner extremity of the locking arm 31 is provided with an opening 34' adapted to accommodate the pin 32.

The outer or free end of the locking arm 31 is curved and provided with teeth 35, which in operation engage the fly wheel of the motor to prevent rotary movement of the fly wheel, and it will be seen that since the fly wheel rotates clock-wise, a wedging action is set up between the fly wheel and the locking arm.

35 The pivoted latch member 16 has connection with the under surface of the supporting plate, through the medium of the pivot pin 36, one end of the latch member 16 extending at right angles to the body portion 40 thereof as at 37, the same being apertured to accommodate one end of the connecting link 38, the opposite end of which has connection with the controlling arm 28 so that movement of the controlling arm 28 causes 45 a relative movement of the latch member 16 to affect the locking of the false cover 11.

From an observation of Fig. 2 which shows the locking arm in an unlocked position, it will be seen that the right angled portion of the arm 26 carries one end of the arm 28 to a position to bring the inner end of the arm 28 laterally of a direct line through the right angled portion of arm 26, lower end of arm 20, and the pivot pin 30 so that the tension of the coiled spring 39 will tend to force a portion of the arm 28 into engagement with the extended portion 20' of the arm 20, to lock the arm 31 normally, out of operation.

60 When it is desired to move the locking arm 31 into a locking position, a suitable key is inserted to operate the tumblers 24, whereupon the key is given an additional rotation to cause the arm 20 to move the arm 26 to move the right angled end thereof

out of the direct line with the pivot pin 30, whereupon the tension of the coiled spring 39 moves the locking arm 31 into engagement with the fly wheel of the motor, to prevent movement thereof.

70 In view of the foregoing disclosure, a detail description of the operation of the device is believed unnecessary.

Having thus described the invention, what is claimed as new is:—

1. In combination with a motor fly wheel, a locking device including a body portion, a pivoted locking arm having teeth formed on one of the edges thereof, means for normally holding the arm out of engagement with the fly wheel, said means including a controlling arm having an elongated opening formed adjacent to one end thereof, a pivot pin on the locking arm and operating in the opening, whereby the locking arm will automatically adjust itself to the fly wheel associated with the lock, and means having connection with the pivoted locking arm for moving the locking arm into its locked position.

90 2. In combination with a motor fly wheel and the casing housing the same, a supporting plate secured to the casing, a false cover having connection with the supporting plate, a depending hook carried by the false cover, 95 said hook adapted to extend through the supporting plate, a locking arm carried by the supporting plate and adapted to be moved into engagement with the fly wheel, means for moving the arm into engagement with the fly wheel, and a latch member operated automatically with the means for moving the arm, for coöperating with the depending hook to lock the false cover to the supporting plate.

100 3. In combination with a motor fly wheel and the casing housing the same, a supporting plate secured to the casing, a locking flange formed along one edge of the casing, said supporting plate having an opening formed therein, a false cover having an inturned end adapted to coöperate with the locking flange, a depending hook carried by the false cover and adapted to extend through the opening in the supporting plate, a pivoted locking arm having teeth formed on one end thereof, said teeth adapted to engage one of the faces of the fly wheel to lock the fly wheel against movement, and means adapted to move simultaneously with the locking arm for coöperating with the hook for locking the false cover to the supporting plate.

110 4. In combination with a motor fly wheel and the casing housing the same, a supporting plate secured to the casing and having a flange formed at one end thereof, a false cover adapted to substantially house the supporting plate, said cover having an inturned end adapted to be positioned over the flange,

- 5 said supporting plate having an opening, a depending hook member carried by the false cover and adapted to pass through the opening, locking means carried by the supporting plate and adapted to move into engagement with the fly wheel to lock the same against movement, a pivoted latch member carried by the supporting plate, and means for connecting the pivoted latch member 10 and fly wheel locking means to cause the latch member to engage the hook member to lock the false cover to the supporting plate, when the locking means is moved in one direction.
- 15 5. In combination with a motor fly wheel and the casing housing the same, a supporting plate secured to the casing, a false cover adapted to substantially house the supporting plate, said supporting plate hav-
- ing an opening, locking means carried by 20 the false cover and extending through the opening, pivoted means carried by the supporting plate and adapted to move into contact with the fly wheel, for locking the fly wheel against movement, and means carried 25 by the supporting plate and controlled by the movement of the first mentioned means for moving into engagement with the locking means for locking the false cover against movement.
- 30 In testimony that I claim the foregoing as my own, I have hereto affixed my signature in the presence of two witnesses.

WILLIAM A. LOWERY.
